UNITED STATES PATENT OFFICE

2,487,259

CYLINDRICAL DOMESTIC REFRIGERATOR

Willard L. Morrison, Lake Forest, Ill.

Application February 9, 1945, Serial No. 576,972

8 Claims. (Cl. 62—116)

1

My invention relates to an improvement in refrigerators and is particularly adaptable to, but not limited to domestic electrical refrigerators.

One purpose is to provide a two temperature domestic refrigerator.

Another purpose is to provide a refrigerator in which a lower storage portion is formed or surrounded by a circumferentially extending evaporator, while the upper portion is located above said evaporator.

Another purpose is to provide improved means for supporting the material stored in a domestic refrigerator.

Another purpose is to provide improved means for closing a domestic electric refrigerator when it is not in use.

Another purpose is to provide a combined door and material support for electric refrigerators, wherein the material stored can be readily, bodily removed from the refrigerator when the door is open.

Other purposes will appear from time to time in the course of the specification and claims.

I illustrate the invention more or less diagrammatically in the accompanying drawings, wherein:

Figure 1 is a vertical section;

Figure 2 is a section on the line 2—2 of Figure 1;

Figure 3 is a section similar to Figure 2 with the door in a different position;

Figure 4 is a section on the line 4—4 of Figure 1;

Figure 5 is a section on the line 5—5 of Figure 1;

Figure 6 is a section on the line 6—6 of Figure 1;

Figure 7 is a section on the line 7—7 of Figure 1, on an enlarged scale;

Figure 8 is a section on the line 8—8 of Figure 7;

Figure 9 is a plan view of an ice tray;

Figure 10 is a section on the line 10—10 of Figure 7, on an enlarged scale;

Figure 11 is a section on the line 11—11 of Figure 3, on an enlarged scale; and

Figure 12 is a section on the line 12—12 of Figure 3.

Like parts are indicated by like symbols throughout the specification and drawings.

Referring to the drawings 1 is any suitable base having lower downward ground engaging strips 2. 3 is a disc of insulating material, such as fiber, cork or the like, mounted on the upper surface of the base 1. It may be positioned for example

2

by a generally central dowel 3a which extends into appropriate recesses in the upper surface of the base 1 and in the lower surface of the insulating disc 3. 4 generally indicates an evaporator having a bottom wall 5, shown as having a downward extension 6 seated in a centering aperture 7 in the upper face of the insulating disc 3. Surrounding the exterior of the insulating disc 3 is an outer wall 8 which may be of sheet metal or any other suitable flexible material and which, when the refrigerator is completed, forms a cylindrical tensional outer housing member. Extending upwardly from the circumferential edge of the evaporator bottom wall 5, is an inner cylinder 9 and an outer cylinder 10. The two cylinders may be of sheet metal and define between them a space 11 which extends circumferentially about the evaporator and which receives a liquid refrigerant for evaporation. The cylinders 9 and 10 are shown as sealed together at their upper and lower edges as at 12 and 13 respectively. One of the cylinders, for example the outer cylinder, may be deformed to provide a series of circumferential passages or enlargements which are in communication with or form part of the space 11 between the two cylinders. I illustrate for example a lower enlargement 14, an intermediate enlargement 15, and an upper enlargement 16. Above the enlargement 16 the walls are sealed together as at 17. Above the sealed area is an additional enlargement 18 the interior of the space defined by which is separate from the space 11. The space within the enlargement 14 serves as a bottom distributing manifold 20 with an inlet member 21. The space within the enlargement 15 is an intermediate distributing space or manifold. The space 22 within the enlargement 16 serves as a discharge manifold. In assembling the device the evaporator 4 is positioned as shown in Figure 1 and the outer housing or layer is positioned surrounding the disc 3 and engaging part of the outer periphery of the base 1. After the tubing which is below described is in position, relatively soft insulation 25 is firmly packed into the space between the outer wall 10 of the evaporator and the wall 8. The result is a provision of a firm self supporting structure. The upper surface of the insulation material 25 may be closed and compacted by any suitable ring or body 26 of somewhat firmer insulating material, such as fiber board. A layer of any suitable heat insulating material 27 may be positioned above it, it being important that no heat conducting material or members extend between the cylinders 8 and 10. Note also that the body

or ring 27 extends inwardly above the upper edge of the evaporator. An upper finishing plate or ring 29 may be positioned upon the body 27, with its downwardly extending inner flange 30 spaced inwardly from and out of heat conducting relationship with the evaporator. The outer upwardly extending flange 31 of the ring 29 receives and centers any suitable inner shell 32 for the upper part of the refrigerator. An outer shell 33 is also employed, which is shown as extending downwardly about the upper edge of the outer cylinder 8 of the lower part of the refrigerator. Any suitable stiffening or supporting or bracing or spacing means 34 may be employed in the form for example of curved wooden strips. 35 indicates any suitable insulation between the shells 32 and 33. The top of the upper refrigerator space may be covered by any suitable roof structure. I illustrate a roof having an outer shell 36, an inner or lower shell 37, and an intermediate insulating material 38. The top strip, or strips 39 may be employed as shown in Figure 1. The upper refrigerator structure, as shown in Figures 2 and 3 has a door opening extending about something near 160 degrees of arc which is filled by the below described door structure. The doorway may have at each side any suitable frame member or stiffening, for example the vertical wooden members 40, 41 to which the edges of the shells 32 and 33 are secured. Any suitable means may be employed for preventing any direct conduction of heat from the exterior to the interior of the refrigerator. It will be understood that any suitable heat break may be employed to separate the inner shell 32 from the outer shell 33, along the vertical posts or frame members 40, 41. Or, if desired, the inner and outer shell may be made of material which does not readily conduct heat, in which event no heat break is necessary. I may for example employ sheets of Bakelite or some other suitable plastic. Suitably hinged in the doorway space is a door generally indicated as 45 which includes an inner shell 46, an outer shell 47, intermediate strengthening strips of wood or other suitable material 48 and vertical end strips 49. 50 indicates any suitable insulation filling the space between the shells and the intervening supports. It will be understood that the provision as to the use of a heat break applies to the doors as well as to the fixed part of the upper portion of the refrigerator. 51 indicates a fixed hinge bracket and 52 a movable hinged portion pivoted to the bracket as at 53. 54 is an exterior bracing element extending across the entire width of the door and carrying any suitable locking device 55 which cooperates with any suitable fixed locking abutment 56. Preferably the locking element is so arranged as to subject the member 54 to tension when the locking lever 57 is moved to the locking position. Thus the door is compressed into position and a tight seal is maintained. I may for example employ any suitable yielding sealing strips 58 which may advantageously be positioned on the door structure itself. I prefer to have the door carry supporting means for the material within the upper part of the refrigerator. I illustrate for example supporting members which include a circumferentially extending ring 60 with an inwardly extending flange 61 with a plurality of transversely extending parallel inverted channels 62 upon which the material to be supported may be positioned but which are separated to permit circulation of air. As shown in Figure 11, I illustrate two such supporting mem-

bers. Any suitable number may be employed, depending upon the size and shape of the refrigerator. Upon the upper of the two trays shown in Figure 11, I illustrate a third tray generally indicated at 110 which may be mounted as upon columns or supports 111, upon the upper of the two above described trays. It is effective to support material which it is desired to keep at low temperature, as the articles positioned thereupon are located immediately below the ice cube freezing evaporator.

In the upper part of the refrigerator I illustrate an ice forming device shown in some detail in Figures 7 to 10. I illustrate for example an upper cold plate A and a lower cold plate B. The upper cold plate A is formed of an upper metal plate 65 and a lower metal plate 66. These plates are sealed at their edges as at 67 and are spaced apart and supported by intermediate braces or connectors 68. A central collar 69 defines an open interior passage 70. The space between the plates 65 and 66 is adapted to receive any suitable liquid refrigerant which may be circulated therethrough for evaporation. The plate B is similarly formed with an upper metal plate 65a, a lower metal plate 66a, a circumferential seal 67a, intermediate braces 68a and a central collar 69a. 71 are any suitable supporting sleeves through which pass bolts 72 by which the plate or freezing structure may be supported from the inner roof shell 31. Any other suitable supporting means may be employed. Positioned on the freezing assembly is a lower drip pan including a circumferentially extending wall 73 with a bottom double wall 74 with insulation 75 between its two layers. After defrosting, the drip pan itself may be removed for removal of the water. The drip pan may for example have an inwardly extending flange 76 provided with a plurality of notches 77 which can be brought into register with lugs 78 outwardly extending from the lower plate B. Therefore, when it is desired to remove the drip pan it is slightly rotated until the lugs and notches are aligned and may then be downwardly withdrawn. Within the space between the upper cold plate A and lower plate B, I may insert any suitable ice tray. I illustrate for example a tray including a bottom disc 130 and a circumferential side wall 131. 132 is any suitable removable grid adapted to separate the water, when frozen, into ice cubes. 133 is a handle lug to which is pivoted as at 134 a bell crank lever having a handle component 135 with its handle bar 136 and a lifting component 137, the lower end of which engages the upper face of the lower plate B. It will be understood that a lift of the handle bar 136, causing the lever component 137 to move in a clockwise direction, will raise the bottom 130 of the ice tray and break the seal or frozen bond between it and the top of the lower evaporator cold plate B, permitting the ice tray to be readily removed. As will appear in Figure 7, only three of the vertical supports 72 are employed, these being spaced 90° apart. Thus 180° of the space between the plates A and B is open, for the insertion and removal of the ice tray structure.

The lateral extension of the base 1, as at 1a serves as a machinery platform. The machine space is surrounded by any suitable louvred side wall structure 80 which includes vertical supports 81. 83 is a top wall or closure through which extends any suitable knob 84. Within the machinery compartment so formed I may position any suitable refrigerating mechanism. I illus-

trate for example a supporting bracket structure 85 which supports any suitable motor 86, and any suitable compressor 87. 88 indicates any suitable condenser which may be employed. 89 is any suitable control valve knob which is accessible through an aperture 83a in the wall 83. It is not normally employed by the user. 90 is a delivery duct along which condensed liquid refrigerant may flow from the receiver 91. It is shown as extending to the space within the enlargement 18. The space is separated as at 18a, whereby the refrigerant makes a substantially complete circuit about the upper portion of the refrigerator before it passes along the duct 92 to any suitable expansion valve 93 the details of which do not form part of the present invention. The refrigerant, at appropriately reduced pressure, flows along the duct 94 to the interior of the bottom evaporator plate structure B. It passes thence by the duct 95 to the interior of the top evaporator plate structure A. It passes thence along the duct 96 to the distributor space 20 within the bottom enlargement 14 of the cylindrical evaporator. It will be understood that the interior of the evaporator is so formed and proportioned that the unevaporated liquid refrigerant evaporates substantially uniformly throughout the space between the cylinders 9 and 10. The refrigerant, now largely or substantially entirely evaporated, escapes from the upper distributor space 22 along the return duct 100 to the compressor 87. From the compressor it passes by the duct 101 to the condenser 88 and thence by the duct 102 to the receiver 91. Any suitable control means may be employed, the details of which do not form part of the present invention. I illustrate for example a control bulb 93a for the expansion valve 93, connected thereto by any suitable duct 93b. The knob 84 may be employed, through any suitable actuating system, to control the temperature of the refrigerating system, the details of such control means not forming part of the present invention. Appropriate means may be employed whereby the operation of the system may be interrupted by a predetermined rotation or movement of the knob 84 for defrosting. It will be understood that, when this defrosting takes place the effect on the cold and well insulated lower evaporator 4 will be very slight and will be insufficient to raise the contents of the lower chamber within the evaporator indicated at C to dangerously near the freezing temperature. I may employ any suitable time limit means whereby, after a predetermined and relatively short period, the system returns to normal after the knob 84 has been set to the cutoff or defrosting position.

With reference to the insulated partition 14, 15, it is effective to prevent exterior frosting of the wall surrounding the ice freezing evaporator or separating it from the warmer storage space. It will be understood that an insulated housing may be extended entirely around the ice cube freezing evaporator, if desired.

I claim:

1. In a refrigerator, a base, an open topped evaporator, positioned on said base, surrounding and circumferentially defining a storage space, a layer of insulation underlying and surrounding said evaporator, and a storage cabinet positioned above said evaporator, the interior of the cabinet being in communication with the storage space surrounded by said evaporator, said cabinet including insulated walls, top and door, and food supporting means mounted on said door and

movable unitarily therewith, said food supporting means extending substantially across the interior of said cabinet when the door is closed.

2. In a refrigerator, a base, an open topped evaporator, positioned on said base, surrounding and circumferentially defining a storage space, a layer of insulation underlying and surrounding said evaporator, and a storage cabinet positioned above said evaporator, the interior of the cabinet being in communication with the storage space surrounded by said evaporator, said cabinet including insulated walls, top and door, and one or more horizontally extending air pervious food supporting shelves mounted on and unitarily movable with said door, said shelves extending substantially across the interior of the cabinet when the door is closed.
3. In a refrigerator, a base, an open topped evaporator, positioned on said base, surrounding and circumferentially defining a storage space, a layer of insulation underlying and surrounding said evaporator, and a storage cabinet positioned above said evaporator, the interior of the cabinet being in communication with the storage space surrounded by said evaporator, said cabinet including insulated walls, top and door, an additional evaporator, adapted to freeze ice cubes, located within and adjacent the top of the cabinet, and food supporting means mounted on said door and movable unitarily therewith, including a portion adapted to support food closely adjacent said last mentioned evaporator.

4. In a refrigerator, a base, an open topped evaporator, positioned on said base, surrounding and circumferentially defining a storage space, a layer of insulation underlying and surrounding said evaporator, and a storage cabinet positioned above said evaporator, the interior of the cabinet being in communication with the storage space surrounded by said evaporator, said cabinet including insulated walls, top and door, said open topped evaporator and said storage cabinet being generally cylindrical and general concentric.

5. In a refrigerator, a base, a compressor-condenser unit mounted on said base, generally cylindrical open topped evaporator mounted on said base, defining a low temperature storage space, insulation surrounding and underlying said evaporator, a cabinet positioned above said evaporator and defining a higher temperature storage space, said cabinet having insulated walls, top and door of substantially thinner insulation than that which surrounds said evaporator, said door constituting the sole access means both to the interior of said upper cabinet and to the interior of said evaporator.

6. In a refrigerator, an insulated cabinet having upper and lower portions, the upper portion having a vertical door opening, a well type evaporator in the lower portion surrounding a lower storage space located at a level below said door opening, a substantially smaller evaporator located adjacent the level of the top of the door opening and being located in an upper storage space defined by the upper portion of the cabinet, and means for supplying refrigerant to said evaporators at substantially the same pressure including a common compressor-condenser unit for the two evaporators, the evaporators being connected thereto in series, the lower evaporator having a refrigerant surface of sufficient area to cool the lower storage space it surrounds to a temperature of the order of the temperature of the refrigerant, the upper evaporator being adapted to cool the upper storage space of the

cabinet to a temperature of the range of 30° to 40° higher than the temperature of the lower portion of the cabinet, the spaces cooled by the two evaporators being in direct communication.

7. In a domestic refrigerator, a base, an open topped evaporator having a circumferential wall surrounding and adapted to cool a lower storage space, insulating bottom and side walls surrounding said evaporator and constituting therewith a lower housing, means for cycling a volatile refrigerant through said evaporator and about said storage space, an additional upper housing extending above said evaporator and surrounding an upper storage space located above but in direct communication with the storage space surrounded by said open topped evaporator, an upper evaporator in an upper part of said upper storage space, and means for cycling a refrigerant therethrough, the surface of said upper evaporator opposed to the storage space being of substantially less area than the surface of said first mentioned evaporator opposed to the storage space, said upper housing including an insulating door.

8. In a domestic refrigerator, a base, an open topped evaporator having a circumferential wall surrounding and adapted to cool a lower storage space, insulating bottom and side walls surrounding said evaporator and constituting therewith a lower housing, means for cycling a volatile refrigerant through said evaporator and about said storage space, an additional upper housing extending above said evaporator and surrounding an upper storage space located above but in direct communication with the storage space surrounded by said open topped evaporator, an upper

5
10
15

evaporator in an upper part of said upper storage space, and means for cycling a refrigerant therethrough, the surface of said upper evaporator opposed to the storage space being of substantially less area than the surface of said first mentioned evaporator opposed to the storage space, said upper housing including an insulating door, said upper evaporator including a plurality of horizontal portions spaced downwardly below the top of the upper storage space and inwardly from the sides of the upper storage space, and in alignment with said insulating door.
